UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

THREAD-CUTTING TEMPLE FOR LOOMS.

Application filed May 17, 1924. Serial No. 714,162.

To all whom it may concern:

Be it known that I, HARRY A. DAVIS, a citizen of the United States, and a resident of Hopedale, county of Worcester, State of Massachusetts, have invented an Improvement in Thread-Cutting Temples for Looms, of which the following description, in connection with the accompanying drawing, is a specification, like characters on the drawing representing like parts.

This invention relates to improvements in thread cutting temples for looms and the object of the invention is to provide a construction which shall secure an effective co-
operation between the movable cutter member and the fixed cutter member.

The object of the invention is further to provide a construction which shall minimize the wear of the cutter members and prevent any wear that does take place from disturbing the accurate and effective character of the cutting operation.

The object of the invention is further to provide and maintain co-operating flat guiding surfaces between the movable cutter member and the temple body throughout the movements of the cutter member.

These and other objects and features of the invention will appear more fully from the accompanying description and drawings and will be particularly pointed out in the claims.

In the drawings:

Fig. 1 is an end elevation partially broken away of a temple embodying a preferred form of the invention.

Fig. 2 is a view in vertical section taken on the line 2—2 of Fig. 1.

Fig. 3 is a view in horizontal cross section taken on the line 3—3 of Fig. 1.

The general construction and operation of a loom temple and temple thread cutter are so well known and familiar to those skilled in the weaving art that it is only necessary to describe and illustrate those features with which the present invention is particularly concerned.

The type of thread cutting temple herein illustrated is that shown in the patent to E. S. Stimpson No. 1,366,034, granted January 18, 1921, but the invention is applicable to other types of temples.

In this construction the bar of the usual temple the forward end of which is shown at 1 has formed thereon and secured thereto

the temple head comprising the pod 2, the cap 3 with the enclosed toothed roll 4 journaled on the studs 5 and the entire bar and head moves forwardly when the lay strikes the depending heel 6.

The temple head is provided with a slot extending fore and aft adjacent the end of the toothed roll 4 to provide for the cutting mechanism. In the present invention one important feature consists in that the wall 7 of this slot which is further from the roll 4 is formed flat throughout its length in order to form a flat guide and accurate bearing for the movable cutter member.

The cutting mechanism comprises as usual two elements, viz, a movable cutter member moved forwardly by the lay and rearwardly by a spring and a relatively fixed cutter member with which the movable member operates in severing the filling.

The movable cutter member is conveniently formed throughout of cast iron as a single casting and provided with a chilled rearward end upon which is formed the cutting edge as disclosed in the said patent to Stimpson. As illustrated, this movable cutter member presents the usual body portion 8 presenting at the rear end the chilled portion of hook shape provided with an inclined cutting edge 9 and the usual depending tail 10 at the forward end. The usual spring 11 coiled about the stud 12 on the temple bar and about the stud 13 on tail 10 acts to project the movable cutter member rearwardly.

An important feature of the present invention consists in that the body of this movable cutter member presents throughout a flat side, as shown in Figs. 2 and 3, which bears throughout against the flat wall 7 of the slot in the temple head. In the construction illustrated only the extreme rearward end of the movable cutter member is relieved at 14 to prevent the filling from being pinched as the cutter member is moved forwardly. It will thus be seen that with the movable cutter member bearing against the flat wall 7 accurate guiding surfaces are provided which insure the accurate movement of the movable cutter member with a minimum amount of wear.

The relatively fixed cutter member is shown as a vertical cutter blade 15 of hardened steel and in the form of a narrow flat plate shouldered and bent at its upper end 110

to form a substantial cylindrical bearing 16. This cutter blade is mounted in the temple head at the front end of the slot and at or adjacent the wall 17 nearer the roll. It is 5 also so mounted as to enable it to press yieldingly against the movable cutter member. This is secured by pivoting the blade at its upper end and pressing it by a spring in the direction of the movable cutter member.

10 In the construction illustrated a shoul- dered bearing screw 18 is mounted in a re- cess in the temple head above the slot and the cylindrical bearing 16 of the vertical blade is journaled on this screw. This al- 15 lows a slight pivoting or swinging of the vertical blade toward and from the mov- able cutter member. The temple head is drilled in transversely to form a cylindrical seat or socket 19 in the pod and in this socket 20 is seated a helical spring 20 which thus abuts against the vertical cutter blade 15 and causes it to press yieldingly against the mov- able cutter member. The extent of this 25 yielding pressure may be varied by varying the tension or the length of the spring 20.

The face of the rearward end of the mov- able cutter member upon which is formed the cutting edge 9 is preferably slightly inclined as in the aforesaid Stimpson patent and the 30 cutting edge co-operates with the edge or corner 21 of the vertical blade 15.

The movable cutter member, it will be re- membered, is actuated at each beat up of the lay because each time the lay beats up 35 it strikes against the depending heel 10 of the movable cutter member and carries the movable cutter member forwardly against the tension of the spring 11. As the lay retracts the spring 11 forces the movable 40 cutter member rearwardly. The movement thus imparted to the movable cutter mem- ber is a combined backward and forward and rocking movement.

With the construction of this invention the 45 vertical cutter blade acts to press yieldingly against the movable cutter member at all times and thus to cause the movable cutter member during its forward and backward and rocking movements to maintain its flat side 8 in contact with the flat wall 7 of the slot in the temple head. These two flat sur- 50 faces being in contact cause the movable cutter member to be guided accurately and re- duces the wear on the movable cutter mem- 55 ber and the temple head to a minimum. There is thus no danger of a movable cutter member floating laterally or of its being notched or worn irregularly by the relatively fixed cutter blade or by shoulders or irregu- 60 larities or steel members or blades frequently employed at the opposite side from the relatively fixed cutter blade. The accurate

movement of the movable cutter member which is thus insured with a minimum amount of wear in turn maintains an effective co-operation between the two cutter members themselves and insures the effective severing of the filling when brought into the field of action of the cutting mechanism. 65

Having thus described the invention what 70 is claimed as new and desired to be secured by Letters Patent, is:

1. A thread cutting temple comprising a head slotted fore and aft adjacent the end 75 of the roll, the wall of the slot further from the roll being flat throughout, a movable cutter member mounted to rock and to move forwardly and backwardly in said slot and presenting a flat side to bear throughout said movements on the flat wall of the slot, and a vertical cutter blade mounted in the head at the front end of the slot at the wall nearer the roll and acting to press yieldingly against the movable cutter member thus to cause it during its movements to bear against 80 and be guided accurately by the flat wall of the slot.

2. A thread cutting temple comprising a head slotted fore and aft adjacent the end 90 of the roll, the wall of the slot further from the roll being flat throughout, a movable cutter member mounted to rock and to move forwardly and backwardly in said slot and presenting a flat side to bear throughout said movements on the flat wall of the slot, a 95 vertical cutter blade mounted for lateral movement in the head at the front end of the slot at the wall nearer the roll, and means acting to press the vertical blade yieldingly against the movable cutter member thus to 100 cause it during its movements to bear against and be guided accurately by the flat wall of the slot.

3. A thread cutting temple comprising a head slotted fore and aft adjacent the end 105 of the roll, the wall of the slot further from the roll being flat throughout, a movable cutter member mounted to rock and to move forwardly and backwardly in said slot and presenting a flat side to bear throughout said movements on the flat wall of the slot, a vertical cutter blade pivoted at its upper end in the head and extending at the front end of the slot adjacent the wall nearer the roll, and a spring seated in the head and 110 abutting the vertical blade and acting to press it yieldingly against the movable cutter member thus to cause the movable cutter member during its movements to bear against and be guided accurately by the flat 115 wall of the slot.

In testimony whereof, I have signed my name to this specification.

HARRY A. DAVIS.
